CLAIM

The ornamental design for an orthopaedic shoe mount, as shown and described.

DESCRIPTION

FIG. 1 is a top view of the orthopaedic shoe mount;

FIG. 2 is a front side view thereof;

FIG. 3 is a back side view thereof;

FIG. 4 is a bottom view thereof;

FIG. 5 is a right side view thereof;

FIG. 6 is a left side view thereof; and,

FIG. 7 is a perspective view thereof.

The broken lines in the drawings depict portions of the orthopaedic shoe mount that form no part of the claimed design.
